RECODER

Carl M. F. Friden, Piedmont, Calif., assignor, by
mesne assignments, to International Business
Machines Corporation, New York, N. Y., a cor-
poration of New York

Application July 7, 1931, Serial No. 549,136

1 Claim. (Cl. 200—38)

My invention relates to recording mechanisms and particularly to a timing mechanism therefore.

An object of my invention is to provide an improved timing mechanism for a recorder.

The foregoing and other objects are attained in the embodiment of the invention shown in the drawings, in which

Figure 1 shows a cross section on a vertical median plane the timing mechanism of my invention.

Figure 2 is a schematic wiring or circuit diagram of a recorder including the timing mechanism of my invention.

Figure 3 is a front elevation of the timing mechanism disclosed in Figure 1.

Fig. 4 is a cross section, the plane of which is indicated by the lines 4—4 of Figure 1.

Figure 5 is a cross section, the plane of which is indicated by the lines 5—5 of Figure 1.

Figure 6 is a cross section, the plane of which is indicated by the lines 6—6 of Figure 1.

Figure 7 is a cross section, the plane of which is indicated by the lines 7—7 of Figure 1.

Figure 8 is a cross section, the plane of which is indicated by the lines 8—8 of Figure 1.

The recorder timing unit is adapted for use in a printing recorder having a step by step register mechanism. In this type of mechanism, a card 356 to be printed is positioned over a movable platen 19 mounted on the core 21 of a solenoid 22. When the card is moved against an abutment 24, contacts 29 and 31 are brought together, the contact 29 being mounted on a flexible arm 32. This closes an electric circuit to the solenoid 22, the circuit being traced from an electrode 36 through a lead or wire 37 to the solenoid and thence through a conductor 38 and a wire 39 to the contact 31. The circuit then extends from the contact 29 and the arm 32 through a wire 42 to an electrode 43. A condenser 44 is connected in parallel with the contacts 29 and 31 by wires 46 and 47.

When the platen 19 rises due to the energization of the solenoid 22, an imprint is made on the card 356 by the register (not shown) and the card is lifted off the abutment 24 so that the resilient arm 32 opens the contacts 29 and 31 and the parts are restored to their initial inoperative positions.

In order that the register mechanism can be set, it is actuated by an arm 201 secured to an armature 202 responsive to energization of an electromagnet 207. The coil 207 is energized at equal intervals to afford an impulse to the reg-

ister mechanism and for this purpose is included in an electric circuit. Connected to the coil 207 is a wire 208 extending to a stationary contact 209 with which a movable contact 211 is normally in abutment. The contacts 209 and 211 are portions of a switch, generally designated 212, which will later be described.

From the contact 211 a lead 213 extends to a movable contact 214 abutted by a stationary contact 216. These contacts form part of a mechanism which will be set forth in detail subsequently. From the stationary contact 216 a conductor 217 is joined to a stationary contact 218 abutted by a movable contact 219 which form part of a mechanism later to be described. The contact 219 is joined by a wire 221 to a lead 222 extending to the wire 42 and thence to the electrode 43. From the other electrode 36 a conductor 223 is joined to the wire 37 and extends to a movable contact 224 while from the coil 207 a wire 226 extends to a lead 227 joined to a movable contact 228.

The contacts 224 and 228 are part of an interrupting mechanism included in the timing unit for periodically sending impulses to the coil 207 to set the register or printing mechanism. The contacts 224 and 228 are mounted on pivoted arms 229 and 231, respectively, each of which rides on one of two similar cams 232 and 233 mounted on a shaft 234. The cams are slightly out of phase on the shaft 234 so that as they revolve the arm 231 first drops from the cam 233 permitting the contact 228 to abut the contact 224 and shortly thereafter the arm 229 drops from the cam 232 causing the contact 224 to separate from the contact 228 thereby again opening the circuit after a momentary closure thereof. The shaft 234 is adapted to revolve once every three minutes or five one-hundredths of an hour so that during this period one impulse is sent to the coil 207.

For rotating the shaft 234 I preferably mount on it a gear 236 which is three times the diameter of a gear 237 mounted on the shaft 238 of a synchronous motor 239. As ordinarily supplied to the trade, the synchronous motor 239 is adapted to be driven from any suitable source of regulated alternating current and causes the shaft 238 to make one revolution each minute so that the reduction between the gears 237 and 236 is proper to afford one rotation of the shaft 234 each three minutes. This timing unit can be replaced by any suitable unit which will afford the desired impulses.

In the present instance, the motor 239 is pro-

vided with a field coil 241 joined by a wire 242 to the lead 223 extending to the electrode 36 and by a wire 243 extending to the lead 42 joined to the electrode 43 so that the timing unit operates continuously and periodically causes impulses in the circuit of the coil 281, preferably, one impulse each three minutes or five one-hundredths of an hour. According to this mechanism, therefore, during the continued operation of the timing unit the register is set at periods of three minutes or five-one-hundredths of an hour.

Although the described mechanism alone is suitable for use in some environments, I prefer that when the time of operation includes working periods and non-working periods, the register mechanism be set only during the working periods and not during the non-working periods. To this end I provide a mechanism generally designated 248, which comprises a frame mounted on a supporting bracket 247. The frame of the mechanism includes a front plate 248, an intermediate plate 249, an intermediate plate 251, and a rear plate 252, from which the bracket 247 extends. All of the plates are suitably joined by through bolts 253 and are spaced by sleeves 254 surrounding the through bolts and interposed between the respective plates.

Mounted between the intermediate plates 249 and 251 is a pair of electromagnetic coils 256 and 257, respectively. The coil 257 is joined to the wire 227 extending to the contact 228 while a wire 258 connects the coils 256 and 257 in series and the wire 222 extends to the coil 256 and to the lead 42 of the electrode 43. The other electrode 36 being connected to the wire 223 through the medium of the lead 37, the contact 224 is likewise in circuit so that upon each closure of the contacts 224 and 228 the coils 256 and 257 receive an impulse and are energized simultaneously with the energization of the coil 281.

Energization of the coils 256 and 257 attracts an armature 259 which is mounted for rotation on a shaft 261 journaled between the intermediate plates 249 and 251. The armature 259 preferably includes a pair of diametrically opposed arms 262 and 263 adapted in one position to lie against a stop pin 264 when the coils 256 and 257 are energized and to be rotated away from the stop pin 264 by a spring 266 one end of which is mounted on a pin 267 situated on the intermediate plate 251 and the other end of which is connected to a pin 268 on the arm 262 of the armature 259. Each impulse energizing the coils 256 and 257 thereby causes a rotational oscillation of the armature 259 against the stop pin 264 while the return movement is effected by the urgency of the spring 266.

Pivoted on the arm 263 of the armature 259 by a pin 269 is a pawl 271 operating in an aperture 272 in the intermediate plate 251. A spring 273 on the pin 269 urges the pawl 271 into engagement with a ratchet 274 having fifteen teeth and mounted to rotate in conjunction with a bushing 276 encompassing a plug 277 fixed in the intermediate plate 251 and forming a journal for the shaft 261.

Since the coils 256 and 257 are energized once each five one-hundredths of an hour or each three minutes, the ratchet 274 is advanced one tooth each three minutes or five one-hundredths of an hour. There being fifteen teeth on the ratchet 274, the ratchet makes one complete revolution each forty-five minutes or seventy-five one-hundredths of an hour. In order to prevent a retrograde movement of the ratchet 274, a detent

278 is pivoted as at 279 on the intermediate plate 251 and is urged by a spring 281 into engagement with the ratchet 274. Mounted to rotate in unison with the ratchet 274 by being fixed to the bushing 276 is a gear 282 having three equally spaced teeth on the periphery thereof. Also mounted on the bushing 276 to rotate in unison with the three tooth gear 282 and the ratchet 274 is a notched disc 283 having in its otherwise uninterrupted periphery three equally spaced arcuate notches in 10 juxtaposition with teeth of the three tooth gear 282.

Journaled in the intermediate plates 249 and 251 is a shaft 284 at one extremity carrying an octagonal gear 286, the periphery of which is 15 defined by eight successive arcuate surfaces adapted to cooperate with the periphery of the notched disc 283 and to prevent rotation of the disc 283 unless one of the arcuate notches of the disc 283 is in a position to pass 20 the projection between adjacent arcuate surfaces on the octagonal gear 286. Carried by the hub of the octagonal gear 286 and turning therewith in conjunction with the shaft 284 is a gear 287 having sixteen teeth and meshing with the 25 three tooth gear 282.

Since the three tooth gear 282 makes one complete revolution in unison with the ratchet wheel 274 in forty-five minutes, one of the teeth of the three tooth gear 282 meshes with the gear 287 30 each fifteen minutes so that the shaft 284 is advanced one step each fifteen minutes. The engagement of one of the teeth on the three tooth gear 282 entails engagement between two of the teeth on the sixteen tooth gear 287 and since the 35 octagonal gear 286 at the same time can rotate because of the position of the notched disc 283, the shaft 284 is given one-eighth of a complete rotation for each one-third of a complete rotation of the ratchet wheel 274, thus the shaft 284 40 makes a complete revolution each two hours.

The other extremity of the shaft 284 is formed to provide a gear 291 having eight equally spaced teeth thereon. This gear 291 is in mesh with a gear wheel 292 mounted on a shaft 293 journaled 45 in the intermediate plate 249. The gear 292 is provided on its periphery with ninety-six teeth and since the eight tooth gear 291 makes a complete revolution once in each two hours, the gear 292 and the shaft 293 make a complete revolution 50 once each twenty-four hours. The shaft 293 carries a timing member including a disc 294 removably mounted on the shaft 293 and preferably divided at least into twenty-four equal spaces 296 separated by radial division lines 297. Each of 55 the division lines is identified by one of a series of consecutive numerals from 1 to 24, inclusive, indicating the twenty-four hours of a day. Preferably, the spaces 296 adjacent the periphery of the disc are further sub-divided into quarter divisions 298 each of which represents fifteen minutes or .25 of an hour.

The timing member 294 is preferably utilized to control the register; that is, to prevent the setting of the register to indicate or cumulate 65 non-working time periods but to permit the setting or cumulation in the register of working time periods. For this purpose the periphery of the disc 294 is made of irregular contour in accordance with the particular conditions under which 70 the machine is operating. As especially shown in Figure 3, the disc is abruptly reduced in diameter at the terminus of the line 297 passing through the numeral 8 and representing 8:00 a. m. This reduced portion of the periphery is 75

generally indicated by the reference numeral 298 and extends to the terminus of the radial line 297 passing through the figure 12 and representing 12:00 noon. Thus, the reduced portion 298 is of a peripheral extent representing the working time period between 8:00 a. m. and 12:00 noon.

The periphery of the disc 294 is then uninterrupted between the termini of the radial lines 297 passing through the numerals 12 and 13 representing 12:00 o'clock noon and 1:00 o'clock p. m. or 13 o'clock. Thus, the peripheral portion generally designated by the numeral 301 of the disc 294 is uninterrupted for the non-working time period between 12:00 o'clock noon and 1:00 o'clock p. m. or 12:00 and 13:00 o'clock.

Again the periphery of the disc 294 is interrupted, as generally indicated by the numeral 302, from the terminus of the radial line 297 passing through the numeral 13, with the interruption extending to a radial line between the lines associated with the numerals 16 and 17. The latter radial line represents half past four o'clock p. m. or half past sixteen o'clock or 16:50 o'clock. Thus, the working period between 13:00 and 16:50 o'clock is represented by an interrupted portion 302 of proportional extent. The periphery of the disc 294 between the terminus of the portion 302 and extending from the radial line between the numerals 16 and 17 representing 16:00 and 17:00 o'clock around the periphery of the disc to the terminus of the radial line 8 representing 8:00 o'clock is uninterrupted and is proportional to the non-working period between half past four o'clock p. m. or half past sixteen o'clock or 16:50 o'clock and eight o'clock a. m. or 8:00 o'clock. During each twenty-four hours the disc 294 makes one complete rotation and the successive portions 299, 301 and 302 pass a given point once.

The irregular periphery of the timing member 294 can be arranged as desired by removing portions of the disc to give any relationship desired between working time periods and non-working time periods. Originally the disc is uninterrupted on its periphery and is cut or interrupted to suit the particular conditions under which the machine is to be operated. If desired, the disc can be of relatively thin metal marked, perforated or scored so that the periphery can easily be mutilated.

The irregularity in the periphery of the disc 294 is utilized to prevent impulses from affecting the setting of the register. Mounted on the front plate 248 is an insulating block 303 on which a lever 304 is pivoted by a pin 306. One end of the lever is provided with a follower 307 adapted to contact the periphery of the disc 294 so that the irregularities thereof oscillate the lever about its pivotal point. The lever 304 at its other extremity carries the movable contact 219 which cooperates with the stationary contact 218 likewise mounted on the insulating block 303. During the time that the uninterrupted portion of the disc 294 is in contact with the follower 307, the contacts 219 and 218 are separated thereby breaking the circuit from the timing unit to the coil 207 so that any impulses originating in the timing unit are not effective on the coil 207 and the register is not set. However, when the interrupted portion of the disc 294 is adjacent the follower 307 the contacts 219 and 218 are gravitally closed so that impulses originating in the timing unit are imparted to the coil 207 and serve to set the register. Thus, the timing unit operates during a predetermined interval of time but the

register operates only during the working time periods comprised in the predetermined interval of time.

Since the disc 294 makes one complete rotation each twenty-four hours, or each day, I preferably utilize the rotation of this disc to effect an automatic setting of the day wheel of the register. Mounted on the disc 294 is a projecting pin 311 adapted to ride over and close a pair of normally open contacts 312 and 313 just before 24:00 o'clock or 12:00 o'clock noon. These contacts are mounted on resilient arms 314 and 315 respectively which are fastened to an insulating block 317 projecting from the front plate 248. The contact 312 is connected by a wire 318 to the conductor 222 while the contact 313 is connected by a wire 319 to an electromagnetic coil 321. The circuit to the electromagnetic coil 321 is completed by a wire 322 extending from the coil to the lead 31.

When the pin 311 on the disc 294 causes the contacts 312 and 313 to abut, the electromagnet is energized, thus setting the day wheel of the register. At exactly midnight, or 24:00 o'clock when the pin 311 rides over the arm 314 of the contact 312 and releases the contact, the resiliency of the mounting arm causes the contacts to spring apart, thus breaking the circuit and de-energizing the electromagnet 321.

The mechanism as so far described controls the impulses from the continuously operating timing unit in such a fashion that the register is actuated to accumulate only working time periods of the total elapsed or predetermined interval of time on a daily basis.

In accordance with my invention I provide means for causing the mechanism of the register to accumulate working time periods for time intervals longer than one day and preferably of the order of one week. For this purpose there is mounted rotatably on the shaft 283 a gear 326 having eighty-four teeth around its periphery. Meshing with the gear 326 is an idler gear 327 mounted freely on a pin 328 disposed on the front plate 248. Adapted to mesh with the gear 327 is a single tooth gear 329 forming an extension of the shaft 284 and conveniently fabricated by cutting away all but one of the teeth of the gear 291. Since the shaft 284 rotates a complete revolution for each two hours and since there are eighty-four teeth on the gear 326, the gear 326 makes one complete rotation each week. In order to prevent undesired movement of the gear 326 there is a bell crank 331 mounted on a pin 332 projecting from the front plate 248 and urged by means of a spring 333 into engagement with the gear 321. The superior urgency of the single toothed gear 329 meshing with the idler gear 327 causes the idler gear to advance the distance of one tooth forcing the bell crank 331 to ride over one tooth and again engage the idler gear 327.

As particularly shown in Figure 4 the gear 326 is provided with a plurality of bosses 334 to which a week timing member 336 is fastened by screws 337. The face of the week timing member is divided into seven spaces 338 separated by radial lines 339 and is preferably afforded indicia, such as 341, giving the names of the days of the week. Although a major part of the periphery of the member 336 is regular in contour, a portion 342 thereof representing a time period from 2:00 o'clock p. m. Sunday until 4:30 o'clock p. m. Sunday provides a projection. In the path of the projection 342 is a lever 343 mounted on a pivot

pin 344 extending from the insulating block 303 and at one end carrying a follower 346. The other end of the lever 343 carries the contact 214 while the cooperating contact 216 is mounted on the insulating block 303. During substantially all of the rotation of the member 336, that is, during all of the days of the week except Sunday, the follower 346 is out of contact with the periphery of the member 336 and the contacts 214 and 216 are in abutment thereby permitting the circuit to the coil 207 to be completed momentarily and under the additional control of the contacts 218 and 219. However, on Sunday between the hours of 2:00 p. m. and 4:30 p. m., for example, the projection 342 contacts the follower 346 and separates the contacts 214 and 216 thus breaking the circuit to the coil 207 and preventing any impulses originating in the timing mechanism during this non-working time period from being communicated to and set in the register.

By providing other timing members similar to the member 294 and the member 336, the mechanism can be arranged so that non-working time during a month or during a year can be prevented from being set in the register by suitably opening the circuit through the coil 207. As I have indicated in Figure 2, there is in the present instance provided a manual switch 212 controlling the contacts 209 and 211. Normally, these contacts are closed but in the event of a

holiday, they are manually separated, thereby interrupting the circuit to the coil 207 and preventing the setting in the register of non-working time periods during the holiday.

It is to be understood that I do not limit myself to the form of the recorder shown and described herein, as the invention, as set forth in the following claim may be embodied in a plurality of forms.

I claim:

A timing device for use in an electric circuit including a plate, a day disc rotatably mounted on said plate and having an irregular periphery, a week disc rotatably mounted on said plate coaxially with said day disc and having an irregular periphery, a first pair of contacts and a second pair of contacts in series in said circuit, a first lever for actuating said first pair of contacts pivoted with respect to said plate and bearing at one extremity on the periphery of said day disc, a second lever for actuating said second pair of contacts pivoted with respect to said plate and bearing at one extremity on the periphery of said week disc, a drive shaft on said plate adapted to rotate, means including an intermittent action timing mechanism for rotating said drive shaft intermittently, and means connecting said day disc directly to said drive shaft and said week disc directly to said drive shaft for rotation thereby at different rates.

CARL M. F. FRIDEN.
